Primary Examiner — Thomas Johannes*Assistant Examiner* — Catherine S Posthauer(74) *Attorney, Agent, or Firm* — Barnes & Thornburg LLP; Michael A. Carrillo(57) **CLAIM**

The ornamental design for a cap, as shown and described.

DESCRIPTION

FIG. 1 is a top perspective view of a cap showing my new design;

FIG. 2 is a top plan view thereof;

FIG. 3 is a side elevational view thereof;

FIG. 4 is a second side elevational view thereof, opposite FIG. 3; and,

FIG. 5 is a bottom plan view thereof.

The broken lines are shown for the purpose of illustrating parts of the article that form no part of the claimed design.

1 Claim, 3 Drawing Sheets(56)
